CLAIM

The ornamental design for a handheld picture reader, as shown and described.

DESCRIPTION

FIG. 1 is a bottom perspective view of a handheld picture reader of the claimed design.

FIG. 2 is a top perspective view thereof.

FIG. 3 is left side view thereof.

FIG. 4 is a right side view thereof.

FIG. 5 is a bottom view thereof.

FIG. 6 is a top view thereof.

FIG. 7 is a rear view thereof; and,

FIG. 8 is a front view thereof.

The broken lines shown in the figures depict portions of the handheld picture reader that form no part of the claimed design.

1 Claim, 7 Drawing Sheets
